UNITED STATES PATENT OFFICE

CHARLES F. OSGOOD, OF CLAREMONT, NEW HAMPSHIRE, ASSIGNOR TO SULLIVAN MACHINERY COMPANY, A CORPORATION OF MASSACHUSETTS

MINING MACHINE

Application filed March 31, 1930. Serial No. 440,309.

This invention relates to mining machines and more particularly to improvements in the feeding mechanisms of such machines.

An object of this invention is to provide an improved mining machine feeding mechanism. Another object is to provide an improved flexible feeding means for a coal mining machine of the continuous cutter, bottom cutting type. A further object is to provide 10 an improved flexible feeding means for a mining machine adapted to operate in accordance with the usual room and pillar practice wherein relatively rotatable feeding members respectively cooperate with advance 15 and receding flexible feeding elements in the feeding and guiding of the machine across the coal face. A still further object is to provide in a feeding mechanism of the aforesaid character a separate and distinct plural speed 20 transmission mechanism for each feed member whereby the latter may be rotated in winding direction either separately or simultaneously at relatively high speed or at relatively low speed or may rotate in unwinding 25 direction under various degrees of frictional resistance or freely as conditions may require. Yet another object is to provide a separate and distinct plural speed planetary transmission for each of the feed members, the planetary 30 transmission mechanisms and feed members being arranged in a novel and improved manner on the machine. These and other objects of this invention will, however, hereinafter more fully appear.

35 In the accompanying drawings there is shown one form which the invention may assume in practice.

In these drawings,—

Fig. 1 is a plan view of a coal mining machine having embodied therein an illustrative form of the improved flexible feeding mechanism.

40 Fig. 2 is an enlarged horizontal sectional view, with parts shown in plan, illustrating the improved flexible feeding mechanism.

45 Fig. 3 is a central longitudinally extending vertical sectional view taken substantially on line 3—3 of Fig. 2.

Fig. 4 is a detail sectional view taken substantially on line 4—4 of Fig. 2 and illus-

trating one of the planetary transmission mechanisms.

Fig. 5 is a detail sectional view taken substantially on line 5—5 of Fig. 3, with parts omitted to facilitate illustration.

As illustrated in the drawings, the improved flexible feeding mechanism is shown embodied in a coal mining machine of the flexibly fed, room and pillar type which generally comprises a low compact machine frame or body 1 slidable on its bottom 2 over the mine bottom and having projecting forwardly therefrom a horizontal plane cutter bar 3 carrying on its margin a cutter bit carrying cutter chain 4 of a usual design. Arranged at the opposite sides of the rear end of the machine frame are feed operating and controlling members 5 and 6 herein in the form of cable winding or haulage drums respectively cooperating with feed and controlling cables 7 and 8. Carried centrally of the machine frame is a motor 9 having its power shaft horizontally disposed and extending longitudinally of the machine frame and operatively connected at its forward end, 55 through usual driving connections, to the cutter chain 4. The rear end of the motor is operatively connected to the feed drums 5 and 6 in an improved manner as hereinafter described. Arranged at the rear end of the machine frame are guide sheaves 10, 11, 12, and 13, while attached at the opposite sides of the front end of the machine frame are similar guide sheaves 14 and 15, and the feed cables are adapted to pass around any preferred guide sheaves during the various operations of the machine in the manner well understood in the mining machine art.

Now referring to the improved driving connections between the rear end of the motor and the feed drums 5 and 6, it will herein be noted that fixed to the rear end of the motor shaft 16 is a spur pinion 17 driving through an intermediate gear 18 a spur gear 19 fixed to a horizontal longitudinally extending shaft 20 suitably journaled within the feed frame section 21. Fixed to this shaft is a worm 22 meshing with a worm wheel 23 which drives, as will hereinafter be described, through separate plural speed planetary transmission 60 65 70 75 80 85 90 95 100

mechanisms, the feed drums 5 and 6, these planetary mechanisms being generally designated 24 and 25 respectively. The planetary mechanism 24 is adapted to effect a plural predetermined speed drive under frictional control of a coaxially arranged horizontal shaft 26 extending transversely of the machine and suitably journaled within the feed frame section 21. Fixed to this shaft is a spur pinion 27 meshing with an internal gear 28 secured to the feed drum 6. The planetary transmission mechanism 25 drives in a similar manner a shaft 29 alined with the shaft 26 and similarly journaled within the feed frame section. This shaft likewise has fixed thereto a spur pinion 31 meshing with an internal gear 32 secured to the feed drum 5. Each of the feed drums is journaled on a shaft 33 formed integral with a detachable side plate 34 secured to the vertical side wall of the machine and is rotatably supported on this shaft by antifriction bearings 35 and maintained against displacement from the shaft by suitable retaining devices 36.

25 As the planetary transmission mechanisms 24 and 25 are generally of the same construction, the description of one will suffice for both. Now referring to the specific structure of the planetary transmission mechanism 24, 30 it will be noted that the worm wheel 23 is keyed at 37 to a sleeve 38 carrying at its outer end a driving pinion 39. The sleeve 38 is journaled upon a bushing 40 which surrounds the enlarged inner end 41 of the shaft 26. A bushing 42 surrounds the sleeve 38 immediately at one side of the worm wheel 23. An annular casing 43 is rotatably mounted on the exterior of the bushing 42 and has a bearing thereon intermediate the worm wheel 23 and the gear 39. The hub of this casing is journaled within a suitable bearing supported by an upstanding bearing bracket formed integral with the feed frame section. The casing 43 comprises a web portion 44 and a cylindrical portion 45 having a suitable friction band 46 on its outer periphery for controlling the rotation of the casing. Mounted within the casing and concentric therewith is a ring-shaped cage 47 in which is carried a plurality of planetary gear pairs 48 (three sets being present but only one shown) rotatable on suitable pins 49 mounted at their ends in the lateral faces of the cage. Each of the members 48 comprises two pinions 50, 51 connected together so as to rotate as a single unit. The pinion 50 of each planetary gear unit has a pitch diameter larger than its companion pinion 51 and is meshed with the driving gear 39. An internal gear ring 52 is arranged within the casing 43 and keyed as indicated at 53 to rotate therewith. Said internal gear meshes with pinions 50 of the planetary gear units. Adjacent the internal gear 52 is a second internal gear 54 free to turn in the casing 43. This internal gear has

a smaller diameter than the internal gear 52 and meshes with the pinions 51 of the planetary gear pairs 48. Attached to the internal gear 54 is an end plate 55 having a clutch member 56 secured thereto and surrounding loosely the shaft 26 and driven through one train of gears as will be shortly explained. A retaining ring 57 is attached to the periphery of the casing 43 by means of suitable bolts 58 and engages the outer face of the ring 55 to form an oil and dust proof enclosure for the gearing therein. The high speed connection to the shaft 26 comprises an annular clutch ring 59 seated within the cage 47 and keyed thereto. This clutch ring is provided with a plurality of inwardly extending clutch jaws 60 adapted to engage with outwardly extending clutch jaws 61 carried by a clutch member 62, slideable longitudinally of the shaft 26. The clutch member 62 is splined to the shaft 26 at 63 so as to effect rotation of the latter, and may be shifted longitudinally along the shaft by any suitable mechanism such as the collar and yoke device 64 having a suitable operating handle 65. In the position of the clutch mechanism 62 illustrated in Fig. 4, the clutch jaws 61 are in neutral position, that is, intermediate and disengaged from the clutch ring 59 of the high speed connection and the clutch member 55 of the low speed connection. The driving connection with the high speed and low speed connections is made by shifting the clutch member 62 to the left or right of its neutral position. A second retaining ring 66 is attached to the outer face of the end plate 55 adjacent the clutch member to form a closure between the end plate 55 and the clutch member 62. The friction band 46 may be of any suitable design and is controlled by a pair of nut members 67 attached to the opposite ends of the brake band and internally threaded with threads of opposite inclination and cooperating with oppositely threaded screw portions 68 upon an inclined operating shaft 69 suitably rotatably mounted within the end wall of the feed frame section. Attached to the upper end of this operating shaft is a hand wheel 70. The planetary transmission mechanism 25 for the feed drum 5 is provided with similar clutch mechanism 71 having an operating handle 72 and a similar brake mechanism 73 having an operating hand wheel 74 conveniently arranged adjacent the operating members 65 and 70 of the transmission mechanism 24.

The operation of the mechanism for effecting rotation at different speeds of the shaft 26 may now be described. High speed drive of this shaft takes place through the pinion 39, planetary gears 50, cage 47, clutch ring 59 and clutch member 62. When the clutch member 62 engages the clutch ring 59 the pinion 39 rotates the planetary gears about their respective axes and as the latter are meshed

with the internal gear 52 keyed to the casing 43 they will either rotate this casing, if the 5
brake band 46 is loose, in the direction opposite to the direction of rotation of the pinion 39, or if the friction band 46 is tightened, undergo orbital motion themselves about the axis of the pinion 39 and carry with them at an equal angular rate the cage 47 on which they are mounted. The cage 47 will of course 10
rotate at a rate less than the rate of angular rotation of the pinion 39. The clutch ring 59 being keyed to the cage 47 will be carried thereafter and in turn may be connected to the shaft 26 by means of the clutch member 62. When a slow speed rotation of the shaft 15
26 is desired, the clutch 62 will be shifted to the right and low speed driving will then take place through gearing as follows: pinion 39, planetary gears 50 and 51, internal gear 54, end plate 55, clutch member 56 and clutch member 62. Under these circumstances there will be a compound epicyclic reduction and the shaft 26 will be rotated at a 20
slow speed in the same direction it previously turned at a high speed.

25 The planetary transmission mechanism 25 operates in a similar manner and it will thus be seen that upon suitable control of the clutch devices and brake bands the feed drums 5 and 6 may be driven in winding direction either separately or simultaneously at relatively high haulage speed or at relatively low speed appropriate for cutting. It 30
will also be noted that under certain conditions either of the feed drums may rotate in unwinding direction under various degrees of frictional resistance under the control of the brake bands 46 or without such resistance upon release of these brake bands. As the 35
40 general mode of operation of a room and pillar mining machine is well-known in the art, and as the operation of the improved transmission mechanism for the feed drums has been clearly described above, further description 45
of the operation of the machine is thought unnecessary.

50 While there is in this application specifically described one form which this invention may assume in practice, it will be understood that this form of the same is shown for purposes of illustration and that the invention may be modified and embodied in various other forms without departing from its spirit or the scope of the appended claims.

55 What I claim as new and desire to secure by Letters Patent is:

1. A mining machine feeding mechanism comprising relatively rotatable feed members each adapted to cooperate directly with flexible feeding means, and separate and distinct motor driven driving connections for said feed members including a plural predetermined speed planetary transmission mechanism for each member, said planetary transmission mechanisms being arranged on alined axes.

2. A mining machine feeding mechanism comprising relatively rotatable feed members each adapted to cooperate directly with flexible feeding means, and separate and distinct motor driven driving connections for said feed members including a plural predetermined speed planetary transmission mechanism for each member, said planetary transmission mechanisms being arranged on alined horizontal axes.

3. A mining machine feeding mechanism comprising relatively rotatable feed members each adapted to cooperate directly with flexible feeding means, and separate and distinct motor driven driving connections for said feed members including a plural predetermined speed planetary transmission mechanism for each member, said planetary transmission mechanisms being arranged on alined horizontal axes extending transversely of the machine.

4. A mining machine feeding mechanism comprising relatively rotatable feed members each adapted to cooperate directly with flexible feeding means, a motor, and separate and distinct driving connections between said motor and each of said feed members including a plural predetermined speed planetary transmission mechanism for each member disposed on a horizontal axis, said planetary transmission mechanisms each having a single friction controlling device for controlling the drive through its different speeds.

5. A mining machine feeding mechanism comprising relatively rotatable feed members each adapted to cooperate directly with flexible feeding means, a motor, and separate and distinct driving connections between said motor and each of said feed members including a plural predetermined speed planetary transmission mechanism for each member disposed on a horizontal axis, said planetary transmission mechanisms each including a shiftable clutch device for selectively effecting different speeds.

6. A mining machine feeding mechanism comprising relatively rotatable feed members each adapted to cooperate directly with flexible feeding means, a motor, and separate and distinct driving connections between said motor and each of said feed members including a plural predetermined speed planetary transmission mechanism for each member disposed on a horizontal axis, said planetary transmission mechanisms each having a single friction controlling device for controlling the drive through its different speeds and including a shiftable clutch device for selectively effecting different speeds.

7. A mining machine feeding mechanism comprising relatively rotatable feeding members arranged in coaxial relation and each adapted to cooperate directly with flex-

ible feeding means, a motor, and a separate and distinct driving connection between said motor and each of said members including a plural predetermined speed planetary transmission mechanism for each member, said planetary transmission mechanisms being arranged on axes parallel to a line parallel to said feed member axes.

8. A mining machine feeding mechanism comprising relatively rotatable feeding members each adapted to cooperate directly with flexible feeding means, a motor, and a separate and distinct driving connection between said motor and each of said members including a plural predetermined speed planetary transmission mechanism for each member, said planetary transmission mechanisms being arranged on aligned axes parallel to a line parallel to the feed member axes.

10. A mining machine feeding mechanism comprising relatively rotatable feed members each adapted to cooperate directly with flexible feeding means, a motor, and separate and distinct driving connections between said motor and each of said feed members including a plural predetermined speed planetary transmission mechanism for each member disposed on a horizontal axis, each transmission mechanism including a single clutch element slidable in opposite directions to effect different speeds.

10. A mining machine feeding mechanism comprising relatively rotatable feed members each adapted to cooperate directly with flexible feeding means, a motor, and separate and distinct driving connections between said motor and each of said feed members including a plural predetermined speed planetary transmission mechanism for each member disposed on a horizontal axis, each transmission mechanism including a single clutch element arranged in axial alignment with the planetary mechanism and slidable in opposite directions to effect different speeds.

11. A mining machine feeding mechanism comprising relatively rotatable feed members disposed on horizontal axes and each adapted to cooperate directly with flexible feeding means, a motor, a gear driven by said motor, and separate and distinct plural predetermined speed planetary transmission mechanisms one individual to each member and both driven by said gear.

12. A mining machine feeding mechanism comprising relatively rotatable feed members each adapted to cooperate directly with flexible feeding means, a motor, a worm driven thereby, a worm wheel driven by said worm, and separate and distinct plural predetermined speed planetary transmission mechanisms one individual to each feed member and both driven by said worm wheel.

13. A mining machine feeding mechanism

comprising relatively rotatable feed members each adapted to cooperate directly with flexible feeding means, a motor, a gear driven thereby, and separate and distinct plural predetermined speed planetary transmission mechanisms one individual to each member, each frictionally controlled at all speeds and both coaxial with and driven by said gear.

14. A mining machine feeding mechanism comprising relatively rotatable feed members each adapted to cooperate directly with flexible feeding means, a motor, a worm driven thereby, a worm wheel meshing therewith, and separate and distinct plural predetermined speed planetary transmission mechanisms one individual to each member, each frictionally controlled at all speeds and both driven by said worm wheel.

15. A mining machine feeding mechanism comprising relatively rotatable feed members each adapted to cooperate directly with flexible feeding means, a motor, a gear rotatable on a horizontal transversely extending axis, and separate and distinct plural predetermined speed planetary transmission mechanisms one individual to each member and both driven by said gear.

16. A mining machine feeding mechanism comprising relatively rotatable feed members each adapted to cooperate directly with flexible feeding means, a motor, a worm rotatable on a horizontal axis, a worm wheel meshing therewith, and separate and distinct plural predetermined speed transmission mechanisms one individual to each member and both driven by said worm wheel.

17. A mining machine feeding mechanism comprising relatively rotatable feed members each adapted to cooperate directly with flexible feeding means, a motor, a gear rotatable on a horizontal transversely extending axis, and separate and distinct plural predetermined speed planetary transmission mechanisms one individual to each member, each frictionally controlled at all speeds and both driven by said gear.

18. A mining machine feeding mechanism comprising relatively rotatable feed members each adapted to cooperate directly with flexible feeding means, a motor, a worm rotatable on a horizontal axis, a worm wheel rotatable on a horizontal axis and driven by said worm, and separate and distinct plural predetermined speed transmission mechanisms one individual to each feed member and both driven by said worm wheel.

19. A mining machine feeding mechanism, relatively rotatable feed members disposed on horizontal axes and each adapted to cooperate directly with flexible feeding means, a motor, and separate and distinct plural speed driving connections between said motor and each of said members and including a planetary transmission mechanism for

each member, each transmission mechanism including a rotatable casing, a brake band for controlling casing rotation, and a shiftable clutch for selectively effecting different speeds.

20. A mining machine feeding mechanism, relatively rotatable feed members disposed on horizontal axes and each adapted to cooperate directly with flexible feeding means,

10 a motor, and separate and distinct plural speed driving connections between said motor and each of said members and including a planetary transmission mechanism for each member,

15 each transmission mechanism including a rotatable casing, a brake band for controlling casing rotation, a rotatable cage mounted in said casing and carrying planetary gears, and a shiftable clutch for selectively effecting different speeds.

20 21. In a mining machine feeding mechanism, relatively rotatable feed members of the same size and diameter and rotatable at like peripheral speeds, said members each adapted to cooperate directly with flexible

25 feeding means, a motor, a gear driven by said motor, and separate and distinct plural predetermined speed transmission mechanisms one individual to each member and both coaxial with and driven by said gear, each

30 transmission mechanism including a frictionally controlled reaction member for controlling all speeds and adapted to be held stationary or freely rotate at will.

22. In a mining machine feeding mechanism, relatively rotatable feed members of the same size and diameter and rotatable at like peripheral speeds, said members each adapted to cooperate directly with flexible feeding means, a motor, a worm driven thereby, a worm wheel driven by said worm, and separate and distinct plural predetermined speed transmission mechanisms one individual to each feed member and both driven by said worm wheel.

23. A mining machine feeding mechanism comprising relatively rotatable feed members each adapted to cooperate directly with flexible feeding means, and separate and distinct motor driven driving connections for said feed members including a plural predetermined speed planetary transmission mechanism for each member, said planetary transmissions being arranged on horizontal axes.

24. A mining machine feeding mechanism comprising relatively rotatable feed members each adapted to cooperate directly with flexible feeding means, and separate and distinct motor driven driving connections for said feed members including a plural predetermined speed planetary transmission mechanism for each member, said planetary transmission mechanisms being arranged on horizontal axes extending transversely of the machine.

25. In a mining machine feeding mecha-

nism, relatively rotatable feeding members disposed on horizontal axes extending transversely of the machine and each adapted to cooperate directly with flexible feeding means, and separate and distinct motor driven driving connections for said feeding members including a plural predetermined speed planetary transmission mechanism for each member whereby said members may be rotated either separately or simultaneously at either of two speeds.

26. In a mining machine feeding mechanism, relatively rotatable feeding members disposed on horizontal axes extending transversely of the machine and each adapted to cooperate directly with flexible feeding means, and separate and distinct motor driven driving connections for said feed members including a plural predetermined speed planetary transmission mechanism for each member whereby said members may be rotated either separately or simultaneously at either of two speeds, said planetary mechanisms being arranged generally on horizontal axes parallel to a line parallel to the feed member axes.

27. In a mining machine feeding mechanism, relatively rotatable feeding members disposed on horizontal axes extending transversely of the machine and each adapted to cooperate directly with flexible feeding means, and separate and distinct motor driven driving connections for said feed members including a plural predetermined speed planetary transmission mechanism for each member whereby said members may be rotated either separately or simultaneously at either of two speeds, each of said planetary mechanisms including a rotatable reaction member controlling the drive at both speeds, and a brake band for controlling rotation of said reaction member.

28. A mining machine feeding mechanism including relatively rotatable feed members each adapted to cooperate directly with flexible feeding means, a motor, separate and distinct plural predetermined speed transmission mechanisms one individual to each member, and driving connections between said motor and said transmission mechanisms including a gear coaxial with said transmission mechanisms and driving both of the same.

29. A mining machine feeding mechanism including relatively rotatable feeding members each adapted to cooperate directly with flexible feeding means and motor operated devices for driving said members either separately or simultaneously in a direction to draw in their respective flexible feeding means at relatively high speed or at relatively low speed including a motor shaft, a horizontal shaft extending longitudinally of the machine and driven by said motor shaft, a transverse shaft driven by said longitudinal shaft,

and separate and distinct plural predetermined speed transmission mechanisms one individual to each member and both driven by said transverse shaft.

5 30. A mining machine feeding mechanism including relatively rotatable feeding members each adapted to cooperate directly with flexible feeding means, and motor operated devices for driving said members either separately or simultaneously in a direction to draw in their respective flexible feeding means at relatively high speed or at relatively low speed including alined shafts one connected to each member, and a separate and distinct plural predetermined speed planetary transmission mechanism for each shaft.

10 31. A mining machine feeding mechanism including relatively rotatable feeding members each adapted to cooperate directly with flexible feeding means, and motor operated devices for driving said members either separately or simultaneously in a direction to draw in their respective flexible feeding means at relatively high speed or at relatively low speed including alined horizontal shafts one connected to each member, and a separate and distinct plural predetermined speed planetary transmission mechanism for each shaft.

15 32. A mining machine feeding mechanism including relatively rotatable feeding members each adapted to cooperate directly with flexible feeding means, and motor operated devices for driving said members either separately or simultaneously in a direction to draw in their respective flexible feeding means at relatively high speed or at relatively low speed including alined horizontal shafts extending transversely of the machine one connected to each member, and a separate and distinct plural predetermined speed planetary transmission mechanism for each shaft.

20 33. A mining machine feeding mechanism including relatively rotatable feeding members rotating on horizontal axes and each adapted to cooperate directly with flexible feeding means, and separate and distinct plural speed transmission mechanisms one individual to each member, each operative to provide a plurality of predetermined speeds and also including speed varying means whereby said members may be independently driven at a wide range of speeds between zero and a predetermined maximum.

25 34. A mining machine feeding mechanism including relatively rotatable feeding means rotating on horizontal axes and each adapted to cooperate directly with flexible feeding means, alined shafts one connected to each member, and separate and distinct plural speed transmission mechanisms one individual to each shaft and each operative to provide a plurality of predetermined speeds and also including speed varying means

whereby said shafts may be independently driven at a wide range of speeds between zero and a predetermined maximum.

In testimony whereof I affix my signature.

CHARLES F. OSGOOD.
